UNITED STATES PATENT OFFICE.

WILLIAM G. BERRY, OF MECHANIC FALLS, MAINE, ASSIGNOR TO COLONIAL COMPANY, OF MECHANIC FALLS, MAINE, A CORPORATION OF MAINE.

PERFORATING-MACHINE.

No. 900,257.

Specification of Letters Patent.

Patented Oct. 6, 1908.

Application filed April 20, 1908. Serial No. 428,132.

To all whom it may concern:

Be it known that I, WILLIAM G. BERRY, a citizen of the United States, residing at Mechanic Falls, in the county of Androscoggin 5 and State of Maine, have invented certain new and useful Improvements in Perforating-Machines, of which the following is a specification.

My invention relates to perforating machines, and more particularly, to machines of the rotary type designed especially for forming series of uniform perforations in sheets or webs of paper or similar material.

One object of my invention is to provide a machine of this character by means of which a comparatively wide web of paper can be perforated in such manner that it may afterward be cut into strips of the required width, having a series of perforations along each 20 edge, such strips being designed for use in certain well known apparatus having sprocket wheels which engage the perforations.

Another object of the invention is to provide improved means for supporting the die plates.

A further object of the invention is to provide an improved construction of rotary punch.

A still further object of the invention is to provide improved means for adjusting the rotary punch to and from the die plates.

With the above and other objects in view, my invention consists in the construction and arrangement of parts hereinafter described, and illustrated in the accompanying drawings, in which:—

Figure 1 is a front elevation of the perforating machine, complete; Fig. 2 is a transverse section thereof on an enlarged scale, taken substantially on the line 2—2 of Fig. 1; Fig. 3 is a fragmentary longitudinal section, on an enlarged scale, through the die plates and the supporting rings therefor; Fig. 4 is a transverse section on line 4—4 of Fig. 3; Fig. 5 is an end elevation of one of the clamping rings hereinafter described; Fig. 6 is an end elevation of the machine as shown in Fig. 1; Fig. 7 is a front elevation of a portion of the supporting frame; Fig. 8 is an enlarged sectional detail on the line 8—8 of Fig. 7; Fig. 9 is a side elevation of one of the punch carrying disks; Fig. 10 is a transverse section of one of said disks; Fig. 11 is

a similar view, showing a slightly different construction.

Referring to the drawings in detail, 1 indicates the frame of the machine, which, as shown may be rectangular in shape. Supported in the frame are a pair of parallel shafts 2, 3. The shaft 2 is journaled in bearings 4, and the shaft 3 is journaled in end bearings 5, and also in a middle bearing or journal box 12, supported by means of a screw threaded standard 11, passing through the lower chord of the frame, and adjustably secured in place by means of lock nuts 13.

As clearly shown in Fig. 8, each of the journal boxes 5 is slightly adjustable in the frame and is held in position by means of a yoke 6. A plunger 7, behind which is a coil spring 8, is arranged in a pocket in the frame 1, and is adapted to bear against the upper side of each of said journal boxes 5. A long stud screw 9, is set into the frame 1 at each end of the machine and is adapted to bear at its end upon the lower side of each journal box 5. By means of these screws it is evident that the journal boxes may be slightly raised and lowered, the spring 8 serving to maintain the parts in contact and a lock nut 10 serving to hold the screw 9 in its adjusted position.

Pinions 14 and 15 are secured to one end of the shafts 2 and 3, respectively and cause them to rotate together. Power may be supplied to the machine through the extended end of one of the shafts, as 3, by means of a driving pulley (not shown).

Mounted on the shaft 2 is a series of spacing rings 16, alternating with annular die plates 19. As clearly shown in Fig. 3, each of these spacing rings comprises a cylindrical body portion supported on the shaft by means of a spider 18. Each spacing ring 16 is provided around each edge with an annular groove 21 adapted to receive the edges of the annular die plates 19, and thus support the same. By means of this construction, the die plates, which are preferably of steel, may be made comparatively thin and light, and hence may be readily manufactured and renewed at slight expense. The die plates 19 are provided with a double row of openings or perforations 20 which may be spaced any desired distance apart.

At one end of the shaft 2, adjacent the

pinion 14, is mounted a clamping ring 23 and adjacent thereto, a supporting ring, 22 having a groove similar to 21 formed in its edge, to receive the corresponding edge of the end die plate. The spacing rings 16 and the supporting and clamping rings 22 and 23 are provided with openings 17 and 24, respectively, for the discharge of the punchings which would otherwise accumulate within the same.

At the other end of the shaft 2 is a supporting ring 25, quite similar in construction to ring 22, and a clamping ring 26, which is screw-threaded on to the shaft. It will thus be evident that by screwing up this ring, the various sections of supporting rings and die plates will be clamped rigidly together and held in position.

Mounted on the shaft 3 and so spaced as to coöperate with the die plates 19, is a series of punch carriers 27, 28. These are clearly shown in Figs. 2, 9, 10 and 11. By reference to these figures it will be seen that the intermediate punch carriers comprise two disk-shaped halves 27, provided on one side with a projecting hub 32 and adapted to be fitted together face to face as shown in Fig. 1. The end punch carriers are similar, except that they are formed of one piece only and are provided with a hub 33 projecting from both faces thereof.

Each punch carrier comprises a disk-shaped body portion having formed in one face thereof near the periphery, an annular groove or channel 28^a. A series of radial openings extend from this channel outwardly to the edge of the disk, and the spacing of these openings corresponds with the spacing of the openings in the annular die plates 19. Within the channels 28^a is located an annular thrust plate 29, held in position by means of screws 31.

The punches, which are indicated by the reference character 30, are substantially straight and uniform in cross-section, and are preferably formed of sections of steel wire or rod. These punches are set into the radial openings in the edge of the disk and are of such size that they may be seated with a driving fit, so as to be held in place against the action of centrifugal force by friction. The punches abut at their inner ends against the thrust plate 29. It will thus be evident that in case any punch becomes broken, or if, for any other reason, it is desirable to remove one of the punches, the thrust ring 29 is first removed from the channel, and the particular punch may then be driven inwardly through the opening and into the channel.

Each of the punch carrying members 27, 28, is preferably mounted on bushings 35, clearly shown in Fig. 11, which are secured to the shaft by means of set screws 34. It will be seen, therefore, that by loosening any set

screw, the corresponding bushing may be shifted longitudinally of the shaft, clear of the member 27, and such member will then drop down out of operative relation with the corresponding annular die plate.

A brace rod 36 extends from one end of the upper part of the frame to the other and is held in position by means of set screws 40. Also journaled in the upper part of the frame in bearings 38, held in position by means of yokes 39, is a shaft or roller 37, over which the paper passes on its way to the perforating mechanism.

It will thus be seen that I have provided a very simple and efficient perforating machine comprising a pair of parallel shafts on which are mounted a series of coöoperating die members which may be adjusted relative to each other, and it is thought that the numerous advantages of my invention will be readily appreciated by those skilled in the art.

What I claim is:—

1. In a perforating machine, a pair of parallel shafts, a plurality of coöperating, annular die members carried by said shafts, journal boxes in which one of said shafts is mounted at and intermediate its ends, and means for adjusting both said end and intermediate journal boxes toward and away from the other shaft.

2. In a perforating machine, a pair of parallel shafts, journal boxes in which one of said shafts is mounted at and intermediate its ends, means for adjusting said journal boxes relative to the other shaft, and spring pressed plungers carried by the frame of the machine, and bearing against said adjustable end journal boxes.

3. In a perforating machine, a shaft mounted in suitable bearings, a series of hollow, cylindrical spacing rings secured on said shaft, and a series of annular die plates supported by said rings between the same.

4. In a perforating machine, a shaft, a pair of spacing rings carried thereby, said rings being provided with annular grooves on their adjacent edges, and an annular die plate disposed between said rings and supported at its edges in said grooves.

5. In a perforating machine, a shaft, and a plurality of alternating spacing rings and annular die plates carried thereby, each of said spacing rings comprising a spider and cylindrical body portion, such body portion having an annular groove formed in each edge thereof for supporting said die plates.

6. In a perforating machine, a shaft, a plurality of alternating perforated, annular die plates and hollow cylindrical spacing rings carried by said shaft, said spacing rings having openings therein for the discharge of the punchings, and clamping rings securing said parts together, and to the shaft.

7. In a perforating machine, a shaft, a

punch carrier mounted on said shaft and comprising a disk shaped member having an annular channel formed in one face near the periphery thereof, radial openings extending from said channel to the edge of said member, and punches secured in said openings, said punches being straight and of uniform section throughout, whereby they may be set into said openings with a driving fit, and, 5 when so desired, driven through said openings into said channel, and thus removed. 10

8. In a perforating machine, a punch carrier comprising a disk-shaped member having an annular channel formed in one face adjacent the periphery thereof, radial openings extending from said channel to the edge of 15 said member, a removable, annular thrust plate secured in said channel, and straight, uniform punch pins frictionally held in said 20 openings, and abutting said thrust plate.

9. In a perforating machine, a pair of par-

allel shafts, a pair of coöperating die members carried by said shafts, and a bushing slidably secured to one of said shafts, and on which one of said die members is mounted, 25 whereby, when said bushing is shifted, said die members are thrown out of coöperative relation.

10. In a perforating machine, a pair of parallel shafts, a series of annular die plates 30 mounted on one shaft, a series of coöperating punch carriers mounted on the other shaft, the intermediate die plates and punch carriers being provided with a double row of 35 openings and punches respectively.

In testimony whereof I affix my signature in presence of two witnesses.

WILLIAM G. BERRY.
